TUBE CLEANER

Oreste J. Bagnoli, Woodcliff, N. J., and Thomas C. Wilson, Brooklyn, and James Henry Young, New York, N. Y., assignors to Thomas C. Wilson, Incorporated, New York, N. Y., a corporation of New York

Application November 29, 1933, Serial No. 700,174

8 Claims. (Cl. 15—104.09)

This invention relates to devices for cleaning the inner walls of tubes, such as boiler tubes, to remove scale and incrustations therefrom. More particularly, the invention is concerned with a novel tube cleaner of the rotary type which functions with a continuous action and which, with minor changes easily made, may be employed either at high or low speeds and with either an electric or a fluid motor as a driving means.

10 Cleaning devices for use in boiler tubes as heretofore constructed have ordinarily included a body and a plurality of working elements carried on pivoted arms or swing frames mounted on the body and moved outwardly therefrom by 15 centrifugal force as the device rotates to bring the elements into contact with the deposit to be removed. Such devices are vibratory in action, since the arms or frames are moved backwardly against the centrifugal force by their impact on 20 the scale and are then moved outwardly as the centrifugal force overcomes the force developed by the impact. The working parts thus remove the scale by chipping or hammering it off and because of this action, the devices are not likely 25 to remove the deposits cleanly and they leave behind minute particles of the scale on the tube wall with the result that the surface is rough and further deposits may readily build up again thereon.

30 A further objection to cleaners in which the contact of the working elements with the deposit to be removed is effected by centrifugal action is that they must be rotated at relatively high speeds in order that the working elements may 35 strike the deposit with sufficient force to remove it. As a consequence, these devices necessitate the use of a high speed motor of either the electric or fluid types and the effectiveness of their action largely depends on their speed 40 of rotation.

The present invention is accordingly directed to the provision of a novel tube cleaning device which is provided with a plurality of working elements which are continuously forced toward 45 cleaning position by means carried within the device so that the elements engage the surface to be cleaned substantially continuously and thus remove the deposit more effectively than has been possible with prior devices. The new 50 cleaner is simple and inexpensive to construct, can be readily assembled and taken apart, and is of compact construction so that it can be used in tubes of small diameter. Also, the device is strong and powerful in action and its small size 55 permits it to be used effectively in small tubes

and also in the curved tubes of modern boilers. The device is preferably driven by an electric motor through the medium of the usual flexible shaft but, with simple changes, it can be converted into a form suitable for use with a fluid motor having a low starting torque as the driving means. The ease with which the device can be assembled and taken apart permits these changes to be made rapidly on the job with ordinary tools.

5 While the principles of the invention may be incorporated in devices of different constructions, one form of cleaner constructed in accordance with our invention includes a body provided with a plurality of radial openings or slots 10 leading outwardly from a central chamber. The cleaning elements take the form of blades mounted within the radial slots and they are confined therein against complete removal by suitable means mounted on the body and removable therefrom. Means are also provided within the central chamber for maintaining the blades 15 in proper working positions in the slots and the means used may include a resilient member which acts continuously on the blades to force 20 them outwardly from the longitudinal axis of the body.

25 With the arrangement described, the working elements or blades of the cleaner are held in their proper working positions in the slots by the action of the resilient member and the maintenance of the blades in this position is not dependent upon centrifugal force. The cleaner will accordingly perform its functions at low speeds 30 of rotation and may be driven by a low speed electric motor. When in use, the blades are acted on by centrifugal force which supplements the 35 action of the resilient member but under any conditions of use, the blades are maintained substantially continuously in such positions as to 40 engage the surfaces to be acted on and their cleaning action is thus continuous rather than intermittent.

45 Cleaning devices operated by fluid motors which have a low starting torque must have working elements which can yield under impact against the deposit, since otherwise the torque of the motor might be insufficient to bring the device up to speed. The present cleaner may be used with such low starting torque motors, however, by minor changes which can be quickly made. The device, therefore, is capable of use 50 with driving motors of all types, although it offers the greatest advantages when driven by an electric motor of either high or low speed.

For a better understanding of the invention, reference may be made to the accompanying drawings, in which

5 Figure 1 is an end view of one form of the new cleaning device.

Figure 2 is a sectional view partly in elevation on the line 2—2 of Figure 1.

Figure 3 is a sectional view on the line 3—3 of Figure 2.

10 Figure 4 is a sectional view partly in elevation on the line 4—4 of Figure 1.

Figure 5 is an end view of another form of the new device.

15 Figure 6 is a sectional view partly in elevation on the line 6—6 of Figure 5.

Figure 7 is a sectional view on the line 7—7 of Figure 6.

20 Figure 8 is a sectional view partly in elevation on the line 8—8 of Figure 5.

Figure 9 is a sectional view partly in elevation on the line 9—9 of Figure 10.

25 Figure 10 is a sectional view partly in elevation of another form of the device.

Figure 11 is a sectional view partly in elevation of another form of the device, and

30 Figure 12 is a perspective view showing the parts of a device similar to that illustrated in Figure 2 in position for assembly.

35 In the drawings, one form of the new tube cleaning device is illustrated in Figures 1 to 4, inclusive, as including a body 20 of generally cylindrical form having a central chamber 21 which is open at one end of the body and extends along the longitudinal axis of the body for nearly the entire length thereof. A plurality of radial openings or slots 22 are formed in the body and lead outwardly from the central chamber and through the curved wall of the body. These slots are also open at the end of the body which contains the entrance to the chamber.

40 Mounted loosely in each slot is a working element 23 in the form of a flat blade. This blade has an operating edge 24 and is provided at its ends with lugs 26. The blades are held in the slots by suitable means carried by the body and, for this purpose, a collar 27 is mounted on the solid end of the body and has an opening through which extends the threaded shank 28 projecting from the body and serving as a means for connecting the device to the driving means. When the device is so connected, a portion of the driving means engages the collar 27 and holds it in position with a portion of it overlying one lug of each blade. A collar 29 is mounted on the other end of the body and has a portion overlying the other lug of each blade. This collar has a tongue 30 which enters one of the slots and prevents the collar from rotating and it is held in place by a bolt 31 which is threaded into the end of the chamber and passes through an opening in the collar. The bolt is locked in position by a washer 32 interposed between the head of the bolt and the collar and having a deformable tongue 33 which may be turned up to engage one flat face of the bolt head. The washer is also provided with a tongue 34 which enters one of the slots.

45 With the construction described, the rotation of the device by a suitable motor would cause the blades to be forced outwardly to a position in which their lugs engage the overhanging portions of the collars. The blades would be maintained in this working position during rotation by centrifugal force but upon engagement of the blades

5 to overcome the centrifugal force and cause the blades to move inwardly until the force of impact was overcome by the centrifugal force, whereupon the blades would be restored to working position centrifugally. The blades would accordingly operate with a vibratory action.

10 In order to maintain the blades in proper working position at all times, regardless of the action of centrifugal force, and thereby avoid the vibratory action, means are provided within the central chamber which act on the blades continuously and tend to force them out of the slots. The means may take various forms but one satisfactory form includes a helical spring 34 lying within the chamber and acting on balls 35 and 36. The inner edge of each blade is then preferably formed with a pair of cam surfaces 37, against which the balls engage, and the expansive force of the spring is transmitted through the balls and cam surfaces to the blades and causes the blades to be forced outwardly until their lugs engage the collars 27 and 29. The blades stay in this position regardless of centrifugal force, although that force supplements the action of the spring when the device is operating.

15 The construction shown in Figures 5 to 8, inclusive is generally similar to that shown in Figures 1 to 4, inclusive, but differs therefrom in certain respects. In the construction shown in Figures 5 and 6, the body 20 is formed with six slots instead of four, and the collar 38 on the solid end of the body is threaded on the shank 28 and extends beyond it to receive a portion of the drive means. At the other end, the body carries a collar 39 which is held in place by a bolt 40 threaded into the end of the chamber in the body. The collar 39 is held against rotation by a pin 41 which lies within an opening in the inner face of the collar and an aligned opening in the end of the body, and the bolt is locked in place by a cotter pin 42 which passes through one of a series of bores 43 through the bolt and has its ends lying in a channel 44 in the face of the collar.

20 The collars 38 and 39 overlie the lugs 26 on the ends of the blades and prevent complete removal 45 of the blades. The latter are held in proper working position by a spring 34 within the chamber which surrounds the shanks of a pair of headed members 45, 46. The shank 45a of the member 45 is a solid rod which enters the hollow shank 46a of the member 46 and the spring acts to force the members apart. The heads of the members engage cam surfaces 37 on the inner edges of the blades, and the spring thus acts, in a manner similar to that of the spring 34 in the Figure 2 construction, to force the blades outwardly and hold them balanced with both lugs on each blade engaging the collars on the body.

25 The construction shown in Figures 9 and 10 is similar to that shown in Figures 1 to 4, inclusive, but in the Figure 10 form, the body is reversed. The blades lie within slots as before and the solid end of the body carries a collar 47 which is threaded on the shank 28 and held in place by a headed pin 48 which passes through a bore through the shank and aligned bores in the collar. At the other end, the body carries the collar 27 which is held in place by a nut 49 on a threaded rod 50 which enters the end of the central chamber 21 in the body. The blades have lugs 26 engaging the collars 27 and 47 and they are held in proper working position by a spring 34 which forces balls 35 and 36 against cam surfaces 37 on the inner edges of the blades.

30 As previously mentioned, it may be necessary 75

in some instances to employ the new cleaner with a motor of low starting torque which might not be able to bring the cleaner up to speed in the tube, if the blades were held firmly in position so that they would not yield readily under impact. When this situation arises, the new cleaner may be modified to meet it by removing the spring ordinarily used and substituting a weaker one. Preferably, however, the spring and balls 35, 36 or members 45, 46 are removed from the central chamber of the body and a short rod or slug 51 is inserted, as shown in Figure 11. With the slug in use, the blades are moved out to working position by centrifugal force as the device rotates, and during the starting of the device when the centrifugal force is relatively weak, the blades may be forced inward by impact. The slug prevents the blades from slipping out of the slots into the central chamber and if the slug were not employed, a blade at one side of the device might slip inwardly into the chamber if the opposite blade were at its extreme outer position.

The substitution of the slug for the spring and balls, or reversely, may be readily performed on the job with simple tools as will be apparent from Figure 12 illustrating the method of assembling the device. The spring and balls are first placed in the central chamber and the blades slipped into the slots. Collars 27 and 29 are then mounted on the body to overlie the lugs on the blades and washer 32 is placed against the end of collar 29 and bolt 31 threaded through it into the end of the chamber. The tongue 33 on the washer is then deformed to lock the bolt in place and the cleaner is ready to be connected to the driving means. These operations can all be performed manually and the only tools necessary are a wrench and a punch or similar implement for deforming the locking tongue.

40 The parts of a device similar to that illustrated in Figure 2 are shown in perspective in Figure 12 in the position for assembly. The parts are the same as those of the Figure 2 form except that the blades 23^a have operating edges 24^a in which 45 are cut a series of parallel slots 25 slightly inclined to the axis of the blade and forming cutting teeth.

We claim:

1. A rotary tube cleaner comprising a hollow 50 elongated body having at least three substantially radial openings therein extending lengthwise of said body and communicating with a central chamber within the body, said body being rotatable about its longitudinal axis, at least three 55 cleaning elements loosely mounted respectively in said openings, and extending substantially radially from said central chamber, each of said elements having a cam surface on the inner edge thereof in said central chamber, a member in 60 said chamber engaging the cam surfaces of all of said cleaning elements, a single resilient means disposed longitudinally in said chamber in engagement with said member and resiliently expansible lengthwise of said body, said resilient 65 means acting through said member and said cam surfaces to force all of said cleaning elements outwardly from said chamber, and means on said body engageable with parts of said cleaning elements to prevent complete removal of said elements from said openings.

2. A rotary tube cleaner comprising a hollow 70 elongated body having openings therein extending lengthwise of said body and communicating with a central chamber within the body, said 75 body being rotatable about its longitudinal axis,

cleaning elements mounted in said openings and extending substantially radially from said chamber, each of said elements having a cam surface on the inner portion of each end thereof, a pair of members in the chamber each engaging the cam surface at one end of each element, resilient means in the chamber interposed between said members and expansible lengthwise of said body, said means acting upon the members to force said elements outwardly from the chamber, and means on the body engageable with parts of said elements for preventing complete removal of the elements from the openings.

3. A rotary tube cleaner comprising a hollow 15 elongated body having openings therein extending lengthwise of said body and communicating with a central chamber within the body, said body being rotatable about its longitudinal axis, a plurality of cleaning elements mounted in said openings and extending substantially radially from 20 said chamber, each of said elements having a cam surface on the inner portion of each end thereof, a pair of members in the chamber each engaging the cam surface at one end of each cleaning element, resilient means in the chamber interposed between said members and expansible lengthwise of said body, said means acting upon the members to force said elements outwardly from the chamber, and removable collars on the 25 ends of the body overlying parts of said elements and preventing the complete removal of said elements from the openings.

4. A rotary tube cleaner comprising a hollow 35 elongated body having substantially radial openings therein extending lengthwise of said body and communicating with a central chamber within the body, said body being rotatable about its longitudinal axis, a plurality of cleaning elements mounted in said openings and extending substantially radially from said chamber, each of said elements having a cam surface on the inner portion of each end thereof, a pair of balls in the 40 chamber each engaging the cam surface at one end of each element, a spring in said chamber extending lengthwise of the body and lying between said balls, said spring forcing said balls against said cam surfaces to force said elements outwardly from said chamber, and means on the 45 body for preventing complete removal of the elements from the openings.

5. A rotary tube cleaner comprising an elongated hollow body having substantially radial openings therein extending lengthwise of said body and communicating with a central chamber within the body, said body being rotatable about 55 its longitudinal axis, a plurality of cleaning elements mounted in said openings and extending substantially radially from said chamber, each of said elements having a cam surface on the inner portion of each end thereof, a pair of members in the chamber each engaging the cam surface at one end of each element, resilient means in the chamber interposed between said members and expansible lengthwise of said body, said resilient 60 means acting upon the members to force said elements outwardly from said chamber, a projection on one end of said body, a driving member secured to said projection and a collar mounted on said projection and overlying parts of said cleaning elements for preventing complete removal of the elements from said openings.

6. A rotary tube cleaner comprising a hollow 70 elongated body having substantially radial open-

ings therein extending lengthwise of said body and communicating with a central chamber within the body, said body being rotatable about its longitudinal axis, a plurality of cleaning elements 5 mounted in said openings and extending substantially radially from said chamber, each of said elements having a cam surface on the inner portion of each end thereof, a pair of headed members within said chamber each engaging the cam 10 surface at one end of each element, a coiled spring within the chamber extending lengthwise of said body and interposed between the heads of said members, said members lying partly within the coils of the spring and being acted upon by the 15 spring to force the elements outwardly from said chambers, and means on the body for preventing complete removal of the elements from the openings.

7. A rotary tube cleaner comprising an elongated hollow body having openings therein extending lengthwise of said body and communicating with a central chamber within the body, said body being rotatable about its longitudinal axis, a plurality of cleaning elements mounted 20 in said openings and extending substantially radially from said chamber, each of said elements having a cam surface on the inner portion of each end thereof, a pair of members in the chamber each engaging the cam surface at one end of each 25 element, resilient means in the chamber interposed between said members and expansible lengthwise of the body, said means acting upon the members to force said elements outwardly from the chamber, and a member at one end of 30 the body having a portion overlying parts of said

elements for preventing the complete removal of the elements from said openings and having another portion for connection to a driving member.

8. A rotary tube cleaner comprising an elongated hollow body having openings therein extending lengthwise of said body and communicating with a central chamber within the body, said body being rotatable about its longitudinal axis, a plurality of cleaning elements mounted in 5 said openings and extending substantially radially from said chamber, each of said elements having a cam surface on the inner portion of each end thereof, a pair of members in the chamber each engaging the cam surface at one end of each 10 element, resilient means in the chamber interposed between said members and expansible lengthwise of the body, said means acting upon the members to force said elements outwardly 15 from the chamber, a collar mounted on one end of the body and overlying parts of said elements, 20 a bolt threaded into the body for securing said collar in place, a washer interposed between said collar and bolt and having a part disposed in a recess in the body, a projection on the other end 25 of the body, a driving member secured to said projection, and a second collar mounted on said projection and overlying portions of said elements for preventing the complete removal of said elements from said other end of the body, said second collar being held in place on said body by 30 said driving member.
